UNITED STATES PATENT OFFICE.

ARROL MOIR, OF KENT, ENGLAND.

SKIP FOR RAISING AND STACKING BRICKS.

Application filed December 21, 1927, Serial No. 241,517, and in Great Britain January 10, 1927.

This invention relates to skips for raising and stacking bricks and its object is to provide a skip into which bricks can be loaded by hand and the load of bricks raised in the skip and automatically deposited in a stacked condition. Thus the cost of transferring bricks, for instance from a ship or barge to a railway waggon or a lorry can be reduced by one half, inasmuch as at each transfer the 10 bricks have to be handled once only.

The skip according to the invention consists of an open bottomed box or frame of a size to contain without undue clearance bricks stacked in piled rows and, beneath 15 each row of bricks, a bar temporarily supported beneath the middle of each row and so guided, when released from the supports, as to descend under the weight of the bricks and become laterally displaced from thereunder. Thus when supporting bars are no 20 longer beneath the respective piled rows of bricks, the skip can be raised leaving the bricks piled in rows wherever the skip has been deposited.

25 The bars conveniently are round rods.

Preferably and advantageously the disengagement of the bars from the said supports is effected automatically, and such disengagement preferably is arranged to occur on raising the loaded skip, the bars being held from displacement by the hoisting slings.

The ends of the bars for instance are guided in grooves or slots extending from about the middle line of the respective row 35 of bricks obliquely downwards to clear of one side of the row. The temporary support of the bar can be provided by a lateral shouldered downwardly inclined notch at the upper end of each guide groove, similar to 40 the notch of a bayonet joint. By the ends of the bars being connected to the hoisting slings, on raising the skip the bars are withdrawn from the notches, so that on deposit of the skip, the bars can, under the 45 weight of the bricks, descend the guide grooves or slots and become laterally displaced from beneath the bricks.

A brick raising and stacking skip operating as above described is illustrated, by way 50 of example, on the accompanying drawing, in which:

Fig. 1 is a side elevation of the skip, the brick-supporting bars being shown in section, and

55 Fig. 2 is a corresponding plan.

Fig. 3 is a side elevation showing the end

of a supporting bar and a portion of the guide groove therefor, and

Fig. 4 is a corresponding sectional view, 60 both on a larger scale.

Fig. 5 is an elevation of gravity catches separated by and about to engage the sling bar, shown in cross-section.

The skip is constituted by an open bottomed box *a* divided by two mutually adjacent partitions *b*, *b* into two compartments each of a width to accommodate, with ample clearance, two rows of bricks *c*.

Each row of bricks *c* is supported on a bar *d* extending from one side to the opposite side of the skip *a*, the ends of the bars *d* protruding outwards through guide slots *e* in the respective sides of the skip *a*.

The guide slots *e* for the ends of the bars *d* extend from about the middle line of the 75 respective row of bricks *c* obliquely downwards to clear of the side of the row. Thus the slots *e* beneath the two outer rows of bricks extend beneath and to beyond the outer end walls *f* of the skip *a*, whilst the 80 slots *e* beneath the two inner rows of bricks extend beneath and to between the two inner partitions *b*, *b*.

At their upper ends the slots *e* have re-curved downwardly inclined notches *e*¹ 85 which provide lateral shoulders for the temporary support of the bars *d* whilst the bricks *c* are being stacked in the skip *a* and prior to raising the loaded skip.

A low partition *g* is provided between the 90 outer and inner rows of bricks *b* to hold the lower layers of the bricks from canting on the supporting bars *d*.

The ends of the supporting bars *d* have eyes *h*, journalled thereon and secured at 95 each end by a nut *i* with interposed washers, as shown in Figs. 3 and 4.

On each side of the skip *a*, the eyes *h* are connected by lengths of chain *j* to eye holes *k* formed in a yoke bar *l*, which is loosely 100 held and freely guided between angle guide bars *m* vertically secured to the sides of the skip *a*.

The yoke bars *l* are respectively connected by chains *n* extending from eye holes *o* there-in to the respective end of a transverse sling bar *p*, which extends transversely across the skip *a* in the space between the two middle partitions *b*, *b*, the ends of this bar *p* protruding through the sides of the skip 110 through a vertical slot *q* in each side.

Rings *r* extend through holes in the trans-

verse sling bar *p* for the attachment of the slings of a crane or other hoisting contrivance.

The bricks are, as shown, stacked in the skip with the bars *d* supported in the bayonet notches *e*¹ of the guide slots *e*.

On hoisting the skip by means of slings secured to the rings *r*, the sling bar *p* is raised towards the position shown in dotted lines *p*¹ in Fig. 1 and by the chains *n* raises the yoke bars *l* on each side in their guides *m*, until, on the entire slack of the chains *j* being taken up, the brick-supporting bars *d* are raised out of the bayonet notches *e*¹ into the upper ends of the guide slots *e*. Continued hoisting raises the skip *a* through the brick-supporting bars *d*.

On thereafter lowering the skip *a* on to a surface, the chains *j* on slackening permit the rows of bricks to depress the bars *d* along the oblique guide slots *e* eventually to beyond the end walls *f* and inner partitions *b* respectively of the skip.

The sling bar *p* on being drawn downwards by the weight of the bricks bearing on the bars *d*, is engaged by pivoted gravity catches *s*. These catches *s* are thrust aside by the descending sling bar *p* and, under the influence of their weighted lower ends, engage by their hooked upper ends over the sling bar *p*. The skip thereupon can be hoisted by the sling bar *p*, without the sling bar *p* being raised in the vertical slots *q* and without the chains *n*, *j* raising the bars *d* in the oblique slots *e*, so that the bricks are left stacked in rows deposited on the surface on to which the skip was lowered.

The sides of the skip *a* transverse to the rows of bricks *c* are suitably cut away as shown to provide easy access to the interior for facilitating placing the bricks in position by hand.

The skip may conveniently be constructed to hold one ton of bricks arranged as shown in four piled rows with the individual bricks in each row arranged with their 9" dimension transversely to their supporting bar and their 4½" dimension vertical.

Claims:

1. A skip for raising and stacking bricks, consisting of an open bottomed box frame, and a bar in said frame, said frame being formed with downwardly inclined notches beneath the middle of a row of bricks in said frame and with slots guiding said bar and extending obliquely downwards from said notches to and clear of one side of said row.

2. A skip for raising and stacking bricks, consisting of an open bottomed box frame, a bar in said frame, said frame being formed with downwardly inclined notches beneath the middle of a row of bricks in said frame and with slots guiding said bar and extending obliquely downwards from said notches to and clear of one side of said row, and means for slinging said frame by said bar.

3. A skip for raising and stacking bricks, consisting of an open bottomed box frame, a plurality of bars in said frame, said frame being formed with downwardly inclined notches beneath the middles of rows of bricks in said frame and with slots guiding said bars and extending obliquely downwards from said notches to and clear of one side of each of said rows, means for slinging said frame by said bars, and gravity catches on said frame engaging said slinging means when lowered relatively to said frame.

In testimony whereof I have signed my name to this specification.

ARROL MOIR.
